UNITED STATES PATENT OFFICE.

ROBERT O. BOARDMAN, OF GRAND RAPIDS, MICHIGAN, ASSIGNEE TO MERGENTHALER LINOTYPE COMPANY, A CORPORATION OF NEW YORK.

TYPOGRAPHICAL MACHINE.

1,212,444.

Specification of Letters Patent. Patented Jan. 16, 1917.

Application filed May 17, 1915. Serial No. 28,521.

To all whom it may concern:

Be it known that I, ROBERT O. BOARDMAN, a citizen of the United States, residing at Grand Rapids, in the county of Kent and State of Michigan, have invented certain new and useful Improvements in Typographical Machines, of which the following is a specification, reference being had therein to the accompanying drawing.

My invention relates to typographical composing machines, such as linotype machines of the general organization represented in Letters Patent of the United States No. 436,532, to O. Mergenthaler, wherein circulating matrices are released from a magazine or magazines in the order in which their characters are to appear in print and then assembled in line, the composed line transferred to the face of a mold, the mold filled with molten metal to form a slug or linotype against the matrices which produce the type characters thereon, and the matrices thereafter elevated and returned through a distributing mechanism to the magazine or magazines from which they started. These machines are frequently equipped with a so-called "font-distinguisher", which is located in advance of the distributing mechanism and serves to prevent the delivery thereto of matrices of improper form or font, that is, matrices of a form or font different from that contained in the particular magazine in use. Ordinarily the matrices are formed in their lower ends with notches, which are differently positioned in the respective fonts, so that only those of a certain font, or rather those having notches in a given location, can pass the font-distinguisher, while those of other forms or fonts are arrested thereby. In the use of such font-distinguishers, when an improper matrix is arrested thereby, the operator is ordinarily compelled to leave his seat at the keyboard and pass to the rear of the machine, and there remove the matrix by hand. This is not only vexatious, but requires considerable time and inconvenience. Moreover, failure to remove the offending matrix at the proper time may lead to other difficulties.

It is the principal aim of my invention, therefore, to avoid these objections and to provide means whereby an improper matrix will be removed from the machine automatically, and without interrupting the oper-

ation of the machine, and without requiring any attention on the part of the operator. The manner in which this object and others are carried out will appear from the detailed description to follow and finally be pointed out in the claims.

In the accompanying drawing, I have shown my improvement in preferred form and by way of example, and as applied to a linotype machine of the usual construction, but obviously it is capable of broader application, and may be embodied in other forms and applied to other styles of typographical machines, such for instance as type setters and the like, and still be comprised within the spirit of my invention.

Generally speaking, I desire it to be understood that I do not limit myself to any specific form or embodiment, except in so far as such limitations are specified in the claims.

Referring to the drawing: Figure 1 is a rear view of a portion of the distributing mechanism, showing my invention applied thereto; Figs. 2 and 3 are somewhat similar views showing the parts in different stages of operation; Fig. 4 is a section on the line 4-4 of Fig. 2; and Fig. 5 is a detail.

After the casting operation, the composed line of matrices X is transported to the distributor box A and advanced progressively therethrough by the transfer device or pusher B toward the lifting finger D, which detaches the matrices from the line, one at a time, and delivers them to the conveying screws C¹, which in turn carry them along the supporting rails A¹ onto the ribbed distributor bar C, whereby they are returned to their proper channels in the magazine.

Referring to Fig. 4, it will be noted that the matrices X are formed in their lower ends with notches X¹, which are located in different positions in unlike fonts, as well understood by those skilled in the art. Arranged in advance of the distributor bar C is the font-distinguisher E, the latter being adjustable laterally so as to register with the notches X¹ in the matrices of the font in use. The distinguisher E is fixed to a spindle E¹ slidably arranged in a sleeve E² supported in the distributor box, the sleeve having an elongated slot E³, through which the distinguisher E projects and by which it is guided in its lateral adjustments. The setting of the distinguisher may be accom-

plished in any desired manner, either manually or automatically. As shown in Fig. 4, it is effected automatically by an arm E^5 which shifts it in one direction against the action of a spring E^4 tending to move it in the opposite direction. The arm E^5 is controlled by the movement of the magazines in the manner shown and described in U. S. Letters Patent 1,080,348, to D. S. Kennedy, 10 so that further description herein will be unnecessary.

The parts so far described, except as hereinafter specified, are or may be of the usual construction, or such as shown and described 15 in the Kennedy patent just mentioned.

As previously stated, one of the chief objects of my invention is to provide automatic means for removing from the machine a matrix of improper form or font detected 20 in the composed line by the distinguisher E . To this end, the rails A^1 are formed at their upper edges with notches A^2 , so that the matrices after their detachment from the line, instead of being guided onto the distributor bar C , will be allowed to drop to a lower level if not otherwise supported. In the normal operation of the machine, the 25 matrices are prevented from dropping into the notches by a bridge F , underlying the rails A^1 and formed at its upper end with tracks F^4 , which guide the matrices by their lower ends onto the distributor bar. The bridge is supported in the distributor box so as to be movable vertically into and out of 30 operative position, it being provided at its opposite edges with tongues F^1 slidably engaging in slots A^3 in the framework of the box. The bridge is held in its upper or operative position by means of a catch or latch 35 E^6 fixed to the sleeve E^3 and engaging beneath a transverse shoulder F^2 on the bridge. In this connection, it is pointed out that the sleeve E^3 , wherein the font-distinguisher E is arranged, is rotatably mounted in the 40 distributor box, so that when the distinguisher is engaged by an improper matrix, the sleeve will be rotated and the catch E^6 thus disengaged from the shoulder F^2 , permitting the bridge F to drop to its lower or 45 inoperative position. As a result, when the offending matrix is moved along the rails A^1 by the screws C^1 , it is given no support by the bridge, and consequently drops into the notches A^2 formed in the rails, so that it 50 fails to engage the distributor bar C and is carried along the rails A^1 and dropped from the end thereof out of the machine, as shown by dotted lines in Fig. 3.

After the passage of the offending matrix, the font-distinguisher E and the connected parts are restored to their original positions by the spring E^4 , before alluded to, it being noted that the spring is of the torsional variety, having one of its ends 55 connected to the spindle E^1 to which the

distinguisher is fixed, and its other end connected to the framework. In order to restore the bridge to operative position, it is provided at its lower end with a second shoulder F^3 , which when the bridge is in its 70 lower position will be engaged by a shoulder D^2 formed on the lifting finger D , so that as the latter is elevated to detach a matrix from the line, it will raise the bridge F to its upper position, when the latch E^6 75 will snap automatically beneath the shoulder F^2 and hold the bridge in such position. The parts will remain in this condition until another improper matrix is detected by the distinguisher E , when the same operation is 80 repeated.

In order to allow sufficient time for an improper matrix to be removed from the machine and for the subsequent restoration of the parts to their normal position, means are 85 also provided whereby the lifting finger D will be held temporarily out of action immediately upon detection of an improper matrix. In the present instance, the latch E^6 is employed to secure this result, it being 90 so arranged that when it is swung out of engagement with the shoulder F^2 of the bridge F by the font-distinguisher E , due to the presence of a foreign matrix detached from the line, its outer end will be located above 95 a shoulder D^1 on the lifting finger, as seen in Fig. 2, it being understood of course that the parts are so related that the lifting finger will stand in its lowermost position at this time. It follows therefore that the lifting 100 finger will be arrested in its next reciprocation, as seen in Fig. 3, without interrupting the operation of the distributing mechanism, that no matrix will be disengaged from the line during this cycle of operation. 105 After the rejected matrix has passed the distinguisher E , its spring E^4 will return it and the connected latch E^6 to their original positions, as before explained, so that the finger D in its following reciprocation will 110 be allowed to detach a matrix from the composed line and restore the bridge F to its operative position.

The operation of the parts will now be clear. Under normal conditions, the bridge 115 F stands in its upper position as shown in Fig. 1, being supported therein by the latch E^6 , which is connected to the font-distinguisher E . When an improper matrix irrespective of its thickness finds its way into 120 the machine, and after being detached from the line by the lifting finger D , it engages the font-distinguisher E and rotates the sleeve E^3 to disengage the latch E^6 from the bridge, allowing the latter to drop to its 125 lower position, as shown in Fig. 2. At the same time, the latch is located above the shoulder D^1 on the lifting finger, standing in its depressed position at the time, and the upward movement thereof is arrested, as shown 130

in Fig. 3. The distributor screws, however, continue to rotate and carry the improper matrix along the rails A¹, but since the bridge F is now in its lower or inoperative position, the matrix drops into the notches A² out of engaging relation with the distributor bar C, and is finally carried off the end of the rails out of the machine, as shown by dotted lines in Fig. 3. As the distributor screws complete their cycle of operation, the lifting finger is slightly depressed and resumes its initial position, as shown in Fig. 2, when its pressure upon the latch E⁶ is relieved and the latter disengaged from the finger by the spring E⁴. The distributor screws now begin their next cycle of operation, and the lifting finger being free from the latch rises to detach a matrix from the line and carries with it the bridge to restore it to its upper or operative position, where it is again held by the latch.

As previously stated, I have shown my invention merely in preferred form and by way of example, and it will be obvious that many variations and modifications will suggest themselves to those skilled in the art without departure from its scope.

Having thus described my invention, its construction and mode of operation, what I claim and desire to secure by Letters Patent of the United States, is as follows:

1. In a typographical machine capable of handling type or matrices of variant fonts, the combination of a group or line of type or matrices, means coöperating therewith to detect the presence therein of a type or matrix of improper font, and matrix removing means actuated by said font detecting means for conducting the improper type or matrix from the machine.

2. In a typographical machine, the combination of a movable font-distinguisher, and matrix-removing means controlled thereby for conducting a type or matrix from the machine.

3. In a typographical machine, the combination of a font-distinguisher adjustable to different operative positions to correspond to type or matrices of different fonts, and matrix-removing means controlled by the font-distinguisher in any of its different positions for conducting a type or matrix from the machine.

4. In a typographical machine, the combination of distributing mechanism, means serving when active to control the delivery of type or matrices thereto and when inactive to permit their automatic removal from the machine, and means actuated by an improper type or matrix to render said controlling means inactive.

5. In a typographical machine, the combination of distributing mechanism, means serving when active to control the delivery of type or matrices thereto and when inac-

tive to permit their automatic removal from the machine, and a movable font distinguisher to govern the action of said means.

6. In a typographical machine, the combination of distributing mechanism, a device to control the delivery of type or matrices thereto, and movable vertically from operative position to prevent such delivery, and means for holding the controlling device in its operative position, the said means adapted to be tripped by an improper type or matrix.

7. In a typographical machine, the combination of distributing mechanism, a device to control the delivery of type or matrices thereto, and movable vertically from operative position to prevent such delivery, means for holding the controlling device in its operative position, and a font-distinguisher for tripping said holding means.

8. In a typographical machine, the combination of distributing mechanism, a device to control the delivery of type or matrices thereto and movable to operative and inoperative position, means whereby an improper type or matrix effects the movement of said controlling device to inoperative position, and automatic mechanism for subsequently restoring the device to operative position.

9. In a typographical machine, the combination of distributing mechanism, means serving when active to control the delivery of type or matrices thereto and when inactive to permit their automatic removal from the machine, means actuated by an improper type or matrix to render said controlling means inactive, and automatic mechanism for subsequently rendering the controlling means active.

10. In a typographical machine, the combination of a group or line of type or matrices, distributing mechanism, a reciprocating member to detach the type or matrices individually from the group or line, a device to control the delivery of the detached type or matrices to the distributing mechanism and movable from operative position to prevent such delivery, means whereby an improper type or matrix effects the aforesaid movement of the controlling device, and means whereby the detaching member restores the device to operative position.

11. In a typographical machine, the combination of a group or line of type or matrices, distributing mechanism, a reciprocating member to detach the type or matrices individually from the line for delivery to the distributing mechanism, a font-distinguisher, and means whereby the font-distinguisher arrests the reciprocating member in its detaching movement without interrupting the operation of the distributing mechanism.

12. In a typographical machine, the com-

- 5 bination of a group or line of type or matrices, distributing mechanism, a reciprocating member to detach the type or matrices individually from the line for delivery to the distributing mechanism, a font-distinguisher, and means whereby the font-distinguisher may render said detaching member momentarily inactive without interrupting the operation of the distributing mechanism.
- 10 13. In a typographical machine, the combination of a group or line of type or matrices, distributing mechanism, a reciprocating member to detach the type or matrices individually from the line, means to control the delivery of the type or matrices to the distributing mechanism after their detachment from the line, and means actuated by an improper type or matrix to render said detaching member and controlling means momentarily inactive, for the purpose described.
- 15 14. In a typographical machine, the combination of a group or line of type or matrices, distributing mechanism, a reciprocating member to detach the type or matrices individually from the line, means to control the delivery of the type or matrices to the distributing mechanism after their detachment from the line, means actuated by an improper type or matrix to render said detaching member and controlling means momentarily inactive, and automatic mechanism for subsequently rendering them active, for the purpose described.
- 20 15. In a typographical machine, the combination of a group or line of type or matrices, a reciprocating member to detach them individually from the line, distributing mechanism, a device to control the delivery of the detached type or matrices thereto, said device being movable from its operative position by an improper type or matrix, and means for preventing the action of the detaching member when the controlling device is in its inoperative position, for the purpose described.
- 25 16. In a typographical machine, the combination of a group or line of type or matrices, a reciprocating member to detach them individually from the line, distributing mechanism, a device to control the delivery of the detached type or matrices thereto, and means controlled by an improper type or matrix for effecting the movement of the controlling device to inoperative position and for preventing the action of the detaching member, for the purpose described.
- 30 17. In a typographical machine, the combination of a group or line of type or matrices, a reciprocating member to detach them individually from the line, distributing mechanism, a device to control the delivery of the detached type or matrices thereto, means controlled by an improper type or

matrix for effecting the movement of the controlling device to inoperative position and for preventing the action of the detaching member, and automatic means for subsequently releasing the detaching member and 70 restoring the controlling device to operative position, for the purpose described.

18. In a typographical machine, the combination of a group or line of type or matrices, a reciprocating member to detach them 75 individually from the line, means for removing an improper matrix from the machine, and means controlled by the operation of the removing means for preventing the action of the detaching member during the operation of said removing means.

19. In a typographical machine, the combination of a group or line of type or matrices, a reciprocating member to detach them individually from the line, distributing 80 mechanism, means to control the delivery of the detached type or matrices to the distributing mechanism, means whereby an improper type or matrix renders said controlling means inactive, and means also controlled by said improper type or matrix to prevent the action of the detaching member while the controlling means are inactive.

20. In a mechanism of the class described, the combination of the movable bridge F, 95 the movable font-distinguisher E, and the latch E⁶ controlled thereby for holding the bridge F in its operative position.

21. In a mechanism of the class described, the combination of the lifting finger D 100 formed with the shoulder D¹, the movable font-distinguisher E, and the latch E⁶ controlled thereby and adapted to engage the shoulder D¹ of the lifting finger and thus to prevent its upward movement.

22. In a mechanism of the class described, the combination of the movable bridge F formed with transverse shoulders F² and F³, the lifting finger D formed with corresponding shoulders D¹ and D², the movable font-distinguisher E, and the latch E⁶ controlled thereby and arranged to engage normally beneath the shoulder F², the said latch adapted to be disengaged from the shoulder by the movement of the font-distinguisher 110 and simultaneously engaged with the shoulder D¹ of the lifting finger D, the shoulder D² of the latter being adapted to engage the shoulder F³ of the bridge F when the latter is tripped by the latch E⁶, all for the purpose 120 described.

23. In a typographical machine, the combination of a group or line of type or matrices, distributing mechanism for separating the type or matrices according to character, 125 means for delivering the type or matrices directly to the distributing mechanism, a feeler to detect the presence of a type or matrix improperly located in the line, and automatic matrix-removing means for con- 130

ducting such improper type or matrix from the machine before it is delivered to the distributing mechanism.

24. In a typographical machine, the combination of a group or line of type or matrices, distributing mechanism, a reciprocating member to detach the type or matrices individually from the line, means to control the delivery of the detached type or matrices to the distributing mechanism, and

means actuated by an improper type or matrix to render said controlling means inactive.

In testimony whereof, I have affixed my signature in presence of two witnesses.

ROBERT O. BOARDMAN.
